UNITED STATES PATENT OFFICE.

DAVID R. SAUNDERS, OF COLUMBUS, MISSISSIPPI.

CAR-BUMPER.

No. 893,381.

Specification of Letters Patent.

Patented July 14, 1908.

Application filed April 21, 1908. Serial No. 428,407.

To all whom it may concern:

Be it known that I, DAVID R. SAUNDERS, a citizen of the United States, residing at Columbus, in the county of Lowndes and State of Mississippi, have invented certain new and useful Improvements in Car - Bumpers, of which the following is a specification.

The object of the present invention is the provision of novel means for retarding the movement of rolling stock and preventing the same from passing over the extremity of the track, and the invention contemplates an improved construction whereby this result is accomplished without any sudden shocks or jars which might have a tendency to injure the rolling stock or the contents thereof.

To this end the invention resides broadly in the provision of a track in which the end portion thereof has an undulating formation so as to provide a series of ridges and intervening depressions over which the wheels of the rolling stock must pass and which serve to utilize the energy of the moving car in imparting an up and down movement thereto.

For a full understanding of the invention and the merits thereof and also to acquire a knowledge of the details of construction and the means for effecting the result, reference is to be had to the following description and accompanying drawings, in which:

Figure 1 is a side elevation of a car retarding track termination embodying the invention, the desired slope being imparted to the said track termination by grading the road bed. Fig. 2 is a top plan view of the same. Fig. 3 is a side elevation showing a slight modification in which the necessary slope is obtained by blocking up the track instead of by grading the road bed as shown in Fig. 1. Corresponding and like parts are referred to in the following description and indicated in all the views of the drawings by the same reference characters.

Referring to the drawings which show one embodiment of the invention, the numerals 1 indicate the rails of the main portion of the track which is level or as near level as possible, the said rails being of the usual T section and being supported upon a road bed of any suitable construction. The rails 2 at the end of the track abut against the respective rails 1 and are disposed in alinement therewith and are bent so as to impart an undulating character to the end portion of the track. These rails 2 preferably have a flattened

formation and engage the flanges of the car wheels, the tread portions of the wheels being held spaced from the rails. This construction is found advisable since in many cars the brake shoes extend downwardly to within a very short distance of the track rails and would otherwise come into contact with the curved portions of the rails 2 and be injured. Guard rails 3 which are bent in a manner corresponding to the rails 2 are secured thereto and engage the flanges of the wheels to guide the said wheels in their movement and prevent derailment of the car. Attention is further directed to the fact that the undulations of the rails 2 are gradually increased in magnitude from the level or main portion of the track to the extremity thereof so that each succeeding ridge over which the car wheels pass is higher than the next preceding ridge and each depression is in a similar manner slightly deeper than the next preceding depression. In this manner the rolling stock is gradually brought to a standstill without the production of any sudden shocks or jars which would have a tendency to injure the same or the contents thereof. This manner of retarding the speed of the rolling stock has a further advantage in that when a train is being backed and the end car reaches the rails 2 the up and down movement of the car imparted thereto by the undulating character of the said rails will send a series of impulses through the train and will warn the engineer in ample time to reverse the engine or bring the train to a stop.

In addition to bending the rails 2 so as to provide the ridges and intervening depressions, the end portion of the track is preferably laid upon a grade of about ten per cent., this grade serving the double function of aiding in checking the movement of the rolling stock and also of enabling the rolling stock to be readily pulled away from the undulating portion of the track. The extremities of the rails 2 are extended upwardly at 4 so that should the car not be stopped before it reaches the end of the track the wheels will be engaged by the said upturned ends 4 which will act in a manner similar to that of the ordinary bumper post. Any suitable means may be provided for supporting the rails 2 and the road bed may either be inclined upwardly to impart the desired grade to this portion of the track, or the rails 2 may be blocked up as found most

desirable. With this construction it will be obvious that before a car reaches the extreme end or termination of the track it will be caused to pass over the undulating rails 5 2 and the energy of the car will be utilized in imparting an up and down vibratory movement thereto. In this manner the car is gradually brought to a stop without the injury which would be incident to the sudden jar produced by a bumper post such as is commonly employed. Attention may again be directed to the fact that the car wheels after reaching the rails 2 roll upon their flanges, thereby preventing the brake 10 mechanism from coming into contact with the rails 2 and causing injury.

Having thus described the invention, what is claimed as new is:

1. A car retarding device embodying an undulating track.
2. A car retarding device embodying an undulating track in which the undulations gradually increase in magnitude.
3. A car retarding device embodying an undulating track, the extremities of the rails being extended upwardly.
4. A car retarding device embodying an undulating track, the undulations gradually increasing in magnitude toward the termination of the track and the extremities of

the rails at the said termination being extended upwardly.

5. A car retarding device embodying an undulating track over which the wheels of the car roll upon their flanges. 35

6. A car retarding device embodying an undulating track, and guard rails coöperating with the rails of the undulating track.

7. A car retarding device embodying an undulating track over which the wheels of the car roll upon their flanges, and guard rails coöperating with the rails of the undulating track to prevent derailment of the car. 40

8. A car retarding device embodying an undulating track over which the wheels of the car roll upon their flanges, the undulations of the track gradually increasing in magnitude toward the termination thereof and the rails of the track being extended 50 upwardly at the said termination, and guard rails coöperating with the rails of the undulating track to prevent derailment of the car.

In testimony whereof I affix my signature 55 in presence of two witnesses.

DAVID R. SAUNDERS. [L. S.]
